UNITED STATES PATENT OFFICE.

DAVID D. GORDON, OF CHICAGO, ILLINOIS, ASSIGNOR TO MCGILL MANUFACTURING COMPANY, OF VALPARAISO, INDIANA.

ELECTRIC SWITCH.

Application filed May 19, 1921. Serial No. 470,871.

To all whom it may concern:

Be it known that I, DAVID D. GORDON, a citizen of the United States, residing at Chicago, in the county of Cook and State of Illinois, have invented a certain new and useful Improvement in Electric Switches, of which the following is a full, clear, concise, and exact description, reference being had to the accompanying drawings, forming 5 a part of this specification.

My invention relates to electric switches and has to do more particularly with certain refinements which go to make up a device which is simpler, easier to assemble and 15 cheaper to manufacture.

My invention has to do more with a well known form of switch of the double acting snap type operable preferably by a universal lever. These switches are used more 20 generally for lamp sockets, ceiling or wall switches where the mechanism is necessarily confined to the smallest practical space.

One of the features of my invention is the provision of an improved frame construction, the features of which will be more 25 particularly pointed out in the ensuing specification and claims.

Referring to the accompanying drawing for a better understanding of my invention—

Fig. 1 is a vertical transverse section showing my improved switch mechanism mounted in a lamp socket;

Fig. 2 is a cross section along the line 35 2—2 of Fig. 1;

Fig. 3 is a detail view of a portion of the switch mechanism alternate to that shown in Fig. 1 and with the switch arm in open position;

Fig. 4 is a detail view of a part of the frame;

Fig. 5 is a detail view of an insulating plate which acts as a support for the frame and also carries the pivot bearings for the 45 switch arm; and

Fig. 6 is a detail view of the U-shaped member of the frame and insulation supporting plate assembled.

Referring more in detail to the preferred 50 form of my invention as illustrated, it com-

prises a U-shaped frame A which has upper and lower legs 7 and 8 respectively each leg having stops 9 against which the plate 10 rests. The frame A is adapted to be secured by screws which pass into threaded 55 holes 11 in the ears 9. The plate 10 which is made of insulating material, preferably fibre, acts to rigidly support the legs 7—8 of the frame A by spanning the same, the said legs fitting in the grooves 12—13 which 60 extend transversely of the plate. Thus the legs are rigidly held against displacement. This plate 10 also carries bearing studs 14—15 to pivotally support the switch arm 16 by means of the forked ends of this arm 65 which rest against the studs. These bearing studs are preferably integral with the plate 10 so as to insulate the switch arm from the rest of the switch mechanism. This switch arm 16 is U-shaped so as to 70 span the operating mechanism and engage the pivot studs 14—15. To operate the switch arm 16 I provide a mechanism comprising an intermediate pawl 17 having alternate pivot positions and provided with 75 alternate hooks 18—19 adapted to alternately engage the upper and lower legs 7—8 of the frame. In Fig. 1 the switch mechanism is shown with the switch arm closed and the operating member 17 in its upper 80 position engaging the leg 7.

Now in order to more positively hold this intermediate member 17 in its proper alternate pivot positions, (as it is to be noted that it is a bodily floating member), I provide guiding recessed pivot bearings 20—21 in the upper and lower legs respectively of the frame. This member 17 is connected at its rear or free end to the switch arm 16 85 by means of a spring 22 hooked at its upper end to an insulating clip 23 which extends through a slot in the end of the switch arm 16. Spring 22 is connected at its inner end to a hook in the yoke of the member 17.

In order to swing the member 17 on its pivots I provide a U-shaped pull member 24 having an opening through the outer end of each arm and through which the outwardly extending lugs 25 of member 17 pass. The yoke end of the U-shaped pull member 100

24 is connected to an operating lever preferably in the form of a universally tiltable lever 26. This connection is effected by means of a link 27 which is passed through 5 a hole in the yoke of the pull member 24 and is held by reason of its large head, as shown in Fig. 2.

The link 27 is connected at its other end to a U-shaped link 28 which hooks through a 10 hole in the end of link 27. Link 28 extends into the hollow universal lever 26, the lever being held in place by the screw 29 which passes therethrough. The operating chain 30 is held between the spring fingers of the 15 clip 28 and this chain may, of course, be of any desired length. The universal lever 26 rests at its pivot end in an annular groove 31 so that when tilted in any direction the groove in the frame and the end of the lever 20 cooperate to prevent the lever sliding out of place and also provide a most effective pivot bearing. Also by means of this construction the mechanism is cheapened considerably 25 over where a separate bearing plate has heretofore been used. That is, by building the frame so as to directly take an annular groove as a seat for the lever, the construction is simplified and cheapened over the 30 previous construction wherein separate elements were used.

The switch mechanism as shown herein is mounted upon an insulating base 32, preferably of treated fibre, the frame being held by means of two screws 33 which pass into 35 the threaded holes 11 of the frame. A threaded contact shell 34 is provided and also a center contact 35 for engagement with the corresponding conductors of the lamp base. The shell 34 is connected to terminal 40 binding post 36 which is adapted to receive one of the outside conductors. The circuit thus passes from this binding post 36, shell 34, through the lamp to center contact 35 which is connected to switch contact 37. 45 Contact 37 is crossed by the switch arm 16 with the opposite switch contact 38 which is connected to the other terminal binding post 39.

50 Now as to the operation of the device and assuming the mechanism is in a closed position as shown in Fig. 1, upon tilting the universal lever 26 or pulling it directly outward, pull member 24 is moved toward the left thereby swinging member 17 about its upper pivot hooks 18 so that its free end moves upwardly. This moves the left end of spring 22 upwardly and as soon as it has passed the dead center or line extending from the center 55 of pivot 15 to the point of spring fastening at the outer end of the switch arm 16, said switch arm suddenly snaps upwardly free of the contacts 37-38 and into its alternate position as shown in Fig. 3. This, it is to be noted, occurs although the lever is held in an operated position. Upon releasing the

lever, spring 22 operates to restore the parts for the next or closing operation. That is, as the operator releases his hold upon lever 26, spring 22 pulls the pivot member 17 toward the right at the same time, through the 70 medium of pivotal connections 25, pulls link 24 and lever 26 toward normal.

It is to be noted that upon completion of the operating movement of the lever, and as the switch arm travels to its upward position, pivot member 17 moves downwardly at 75 its right end until the lower hooks 19 rest upon the upper surface of the leg 8 of the frame. Now when the operator releases his hold upon the lever, spring 22 draws member 17 toward the right until the lower hooks 19 thereof drop down over the end and through the slots 21 of the lower leg 8 of the switch frame, as shown in Fig. 3. This movement also, of course, seats the lever 26. 80 The parts are thus in position for their alternate movement so that should the lever 26 be actuated again the pivot member 17 now swings about its lower pivot hooks 19 to move the spring 22 beyond its dead center 85 and thus move the switch arm again into its closed position as shown in Fig. 1. Upon releasing the lever 26, it will again restore to its seat permitting the movement of link 24 and pivot member 17 into the position indicated in Fig. 1. 90

Thus it will be seen that each tilting of the lever 26 effects a snap action of the switch arm, one movement of the lever closing the switch and the next movement opening it, etc. 100

I claim:

1. A switch mechanism comprising a U-shaped frame having laterally extending lug stops, an insulation mechanism supporting plate fitting over the legs of the frame, and means for holding the plate against said stops. 105

2. A switch mechanism comprising a U-shaped frame, and an insulation mechanism supporting plate fitting over the legs of the frame, a switch arm supported by said plate, arm operating mechanism positioned between the legs of the frame, and operatively 110 connected to the switch arm.

3. A switch comprising a legged frame, switch mechanism positioned between legs of the frame, an insulation plate spanning the frame legs, a switch arm pivotally supported by said plate, and a spring connection extending from the switch mechanism to the switch arm for holding the arm against the plate and the plate against the frame. 115

4. A switch mechanism comprising a switch-arm operating member having alternate pivot hooks and a frame having guiding recessed alternate pivot bearings for engagement by the pivot hooks. 125

5. A frame for a switch mechanism operated by an end seated universally tiltable 130

lever, said frame including a sheet metal base having an annular recess impressed in one face thereof to act as a seat for the lever.

6. A switch mechanism comprising a frame having a pair of legs, an insulating plate for supporting the switch mechanism embracing the legs of said frame and inter-

locked therewith and means on said plate for pivotally supporting a movable switch element.

10 In witness whereof, I hereunto subscribe my name this 12th day of March A. D., 1921.

DAVID D. GORDON.
